UNITED STATES PATENT OFFICE.

CASSIUS M. BARTHOLOMEW, OF COLUMBUS, OHIO, ASSIGNOR, BY DIRECT AND MESNE ASSIGNMENTS, TO WILLIAM F. LEONARD AND TOLLEN F. KIRKPATRICK, OF SAME PLACE.

ELEVATOR.

SPECIFICATION forming part of Letters Patent No. 651,562, dated June 12, 1900.

Application filed July 29, 1899. Serial No. 725,467. (No model.)

To all whom it may concern:

Be it known that I, CASSIUS M. BARTHOLOMEW, a citizen of the United States, residing at Columbus, in the county of Franklin and State of Ohio, have invented certain new and useful Improvements in Elevators; and I do hereby declare the following to be a full, clear, and exact description of the invention, such as will enable others skilled in the art to which it appertains to make and use the same.

In passenger-elevators many accidents occur through a tardy or premature operation of the door or through undue haste of passengers to get into or out of the car regardless of whether the car is in motion. In some cases when the motor apparatus is faulty and the operator has temporarily absented himself from the car the car will automatically drop away from the landing, involving trouble and danger.

One object of my present invention is to provide improved mechanism whereby the door cannot be opened until the car has been stopped properly at the landing and whereby the car cannot be moved to another floor until the door has been closed; and, further, it is my object to provide means whereby the car cannot move any considerable distance from a landing in the absence of the operator.

In the annexed drawings, in which I have shown one embodiment of my invention, Figure 1 is a vertical sectional view of an elevator-shaft and a car therein equipped with an embodiment of my present invention. Fig. 2 is a view in elevation looking from the exterior of the shaft toward the door thereof, showing the door closed; but the door-closing lever is in the position to which it is thrown by the movement or passing of the car. Fig. 3 is a view in perspective, parts being broken out to show cams for automatically controlling at a floor the motor-controlling lever.

Fig. 4 is a perspective view illustrating in detail the door-closing lever and door-latching devices. Fig. 5 is a perspective view illustrating in detail, on a scale larger than that of Fig. 1, the parts operated by the motor-controlling lever. Fig. 6 is a perspective view illustrating in detail the devices for withdrawing the door-closing lever from the closed door.

On the several views like characters of reference mark corresponding parts.

1 designates the walls of an elevator-shaft, 55 2 a sliding door suspended on rollers for closing an opening from the floor into said shaft, and 3 a car or carriage to move in said shaft. In the instance shown the apparatus for operating the door 2 comprises a weighted cord 2^a, attached to the upper portion of the door 60 and passing over a pulley in the side of the shaft, said weighted cord tending to pull the door to its open position, and a lever 5, pivoted in the floor and furnished with a spring 5^a, tending to close the door. Attached to the 65 lever 5 is one end of a cord 5^b, while the other end of said cord is attached to block 5^c, sliding on a bar 5^d, arranged vertically at the side of the shaft. The cord 5^b passes between a pair of stationary rollers 5^e, so that 70 if the sliding block 5^c be drawn up or down from its middle or normal position the lever 5 is removed from the door and the weighted cord left free to pull the door open as soon as unlatched, as hereinafter explained. It may 75 be here stated that a spring for the lever of greater power than the weighted cord is employed, so that normally the door is held closed. The devices for moving the block 5^c consist of two boot-shaped dogs 6, pivoted on 80 the outer side of the car, said dogs having springs 6^a to hold their toes normally protruded, so that they shall strike the block 5^c and carry it up or down, according to the direction in which the car is moving. In order 85 that the dogs may be liberated from the block 5^c when the lever has been drawn the required distance from the door, a bar 7, having cam projections 7^a, is arranged in the elevator-shaft parallel to the path of the motion of the dogs, so that the cam projections 90 shall act on studs 6^b to draw the dogs from engagement with the block.

Arranged in the shaft adjacent the lever 5 is a frame 8, having a horizontal portion 8^a, 95 provided with a notch 8^b, (see Fig. 4,) into which a pivoted pawl 5^c on the lever 5 drops to hold the lever in its withdrawn position. (See Fig. 2.) In this frame also is arranged a bar 9, having at its end near the door-opening an elongated eye 9^a, into which projects 100 the end of a bell-crank lever 10, constituting

a latch that is journaled in the floor near the corner of the door-opening, so that when said bar 9 is moved toward the door-opening the latching end of said crank-lever will be raised 5 to abut against a shoulder on a bar 2^b, extending across the door to prevent the opening of the door, and when said rod 9 is moved in the opposite direction the said latching end shall be lowered and permit the opening 10 of the door. The opposite end of the rod 9 is furnished with roller-studs 9^b, for the purpose hereinafter explained, and with a gravity-dog 9^c, the upper end of which is formed to lift the pawl 5^f out of the notch 8^b when the 15 rod 9 is moved toward the door.

The elevator-car is shown to be provided with an ordinary handled lever 11 for controlling the motor that operates the car; but this lever has longitudinally movable upon 20 it a bar 11^a, with a laterally-projecting pin 11^b and a spring 11^c connecting a handle 11^d on bar 11^a with the lever 11, so that said pin is normally depressed. The handle 11^d extends through a longitudinal slot in the lever 25 11. By taking the handle of the lever and the handle of the bar 11^a in the hand the pin 11^b can be raised or lowered at will.

Secured to the wall of the elevator-car adjacent the motor-controlling lever 11 and in 30 a plane parallel to the plane of oscillation of the said lever is a plate 12, having a slot 12^a concentric with the fulcrum of said lever; but the wall of said slot is open at its upper side, as indicated at 12^b, such opening being 35 located opposite that position of the pin 11^b when the motor-controlling lever is in position for stopping the operation of the motor.

Pivoted to the wall of the car at the left of the plate 12, as seen in Fig. 1, is a bell-crank 40 lever 13, having pivoted to the end of its upper or horizontal arm a link 13^a, having a closed slot, preferably concentric with the slot 12^a, in which projects and remains the pin 11^b. The vertical or dependent arm of 45 the bell-crank lever 13 is bifurcated to straddle a pin 14^a on a horizontally-sliding bar 14, arranged on the wall of the car below the plate 12. This plate carries a vertically-arranged bar 14^b, having its ends beveled or 50 pointed. This bar 14^b is placed to stand beyond the side of the car, and its path of motion lies between the roller-studs 9^b on the bar 9.

Pivoted in the floor of the car between the 55 lever 11 and plate 12 is a bar 15, having a recess or notch 15^a at its upper end. The bar 15 is pivoted, so as to oscillate in a plane parallel to the plane of oscillation of the motor-controlling lever, and its recess 15^a coincides horizontally with the slot 12^a in the plate 12. Therefore when the pin 11^b, and with it the link 13^a, is depressed, so that the pin rests in the recess 15^a, the lever 11 and the bar 12 oscillate together, the said pin 60 moving in the slots of both the link and plate. The pin 11^b cannot, therefore, be let into or removed from said recess until lever 11 is

brought to its motor-stopping position—that is, until the pin is brought opposite the opening 12^b.

To hold the bar 15 normally, but yieldingly, with its recess 15^a under the opening 12^b, it is linked by means of a rod 15^b, of proper length, to the end of a spring 15^c, secured under the floor of the car, the bent end of the rod passing through a slot 3^a in the floor of the car. (See Fig. 3.) Connected to this bent end of the rod 15^b is the arm of a bell-crank lever 15^d, while the other arm of the bell-crank lever has its end protruding beyond the side of the car. This bell-crank lever is also best fulcrumed horizontally to the under side of the car, as seen in Fig. 3.

Secured to the side of the elevator-shaft, so as to lie in the path of motion of the protruding end of the bell-crank lever 15^d, are cam-blocks 16. These blocks are arranged one a little above and the other a little below the plane of the floor, so that their adjacent cam-surfaces when acting on the end of the bell-crank lever 15^d shall throw the lever 15 (and also lever 11 when connected therewith) to a position to reverse or stop the motor.

In connection with the bell-crank lever 13 there is employed a device for automatically locking the same while the car is in motion, comprising a bolt 17, upon which is a spring-supported collar 17^a, adapted to be depressed by the centrifugal action of balls 17^b, whirled by the looped portion 18^a of fixed cord 18, passing through the car, said looped portion running over stationary pulleys 19, fixed to the side of the car, and around a pulley 17^c, to which the balls are hinged. This bolt 17 and the centrifugal device are supported in 100 a bracket 20, secured to the wall of the car, so that the bolt shall be thrown into a recess in the bell-crank lever 13 to lock said lever in the running position of the parts—that is, when the link 13 is raised and the door 105 latched—and draw the bolt 17 from the recess when the car is at rest.

The operation, which may be readily understood by those skilled in the art from the foregoing description, is as follows: Let it be 115 supposed that the car shown in Fig. 1 is ascending. In this case the upper dog 6 will strike the block 5^c and draw the door-closing lever 5 to the position indicated in Fig. 2, where it will be held by the engagement of 120 the pawl 5^f with the notch 8^b. After the dog 6 is withdrawn from the block 5^c by the cam 7^a the block may drop by gravity to the position indicated in Fig. 2. By moving the lever 11 to the middle of the link 13^a the car 125 can be stopped at the landing, and when so stopped the bolt 17 is of course withdrawn from the notch in the lever 13. Then by releasing the handle 11^d the pin 11^b drops into the notch 15^a, the lever 13 throwing the bars 130 14 and 9 to the left as viewed in Fig. 1, and consequently the latch 10 down, allowing the weighted cord to draw the door open. In 135 this position of the parts the operating-le-

ver 11 is free to be oscillated; but the car cannot be moved any considerable distance either above or below the landing because of the cam-blocks 16, which will automatically reverse the operating-lever. Therefore in order to move the car to a landing above or below the pin 11^b must be lifted entirely out of the slot 12^a, and this lifting carries with it the link 13^a, and therefore throws the bar 9, with its gravity-dog 9^c, to the right as viewed in Fig. 1, thus lifting the latching-pawl 5^f of the lever 5 and allowing said lever to close the door; but the pin 11^b cannot be lifted entirely out of the slot 12^a until the door is closed, because of the contact of the latch with the bar 2^b, so that it will be impossible to put the car in motion to take it to a floor above or below until the door is entirely closed and latched. It will be noted that after the pin 11^b has been lifted out of the notch 15^a the lever 15 is free to be oscillated by either of the cams 16 without affecting the motor-operating lever 11 and that at all times, except when affected by said cams 16, the lever 15 is held by the spring 15^c, so that its notch 15^a stands directly under the opening 12^b.

What I claim, and desire to secure by Letters Patent, is—

1. In combination with an elevator-shaft, a door in an opening to said shaft, means for automatically opening the same, a device for latching said door in closed position, a car in said shaft, means on the car for operating said latching device, and a governor on the car operated by the motion of the car to lock the door-latch-operating devices, substantially as described.

2. In combination with an elevator-shaft, a car in said shaft, a door in an opening to said shaft, means for automatically opening the same, a device for latching the same in closed position, means on the car for operating said latching device, and means on the car operated by the motion of the car to lock the door-latch-operating devices while the car is in motion and unlocking said lock when the car stops, substantially as described.

3. In combination with an elevator-shaft, a car in said shaft, a door in an opening to said shaft, means for automatically opening the same, a device for latching the same in closed position, means on the car for operating said latching device, a lock operated by the motion of the car to lock the door-latch-operating devices, a motor-controller and means on the motor-controller for operating the door-latch-operating devices when the car has stopped, substantially as described.

4. In combination with an elevator-shaft, a car in said shaft, a door at a landing to said shaft, devices in the car for controlling the motor for said car, cams 16 arranged in said shaft, a device 15 arranged to be actuated by said cams, and means for connecting and disconnecting the motor-controller and the device 15, substantially as described.

5. In combination with an elevator-shaft a car to move in said shaft, a door in an opening to said shaft, means for automatically opening the same, a device for latching the same in closed position, means on the car for operating said latching device, a motor-controlling device in said car, cams 16 arranged in said shaft, a device 15 arranged to be actuated by said cams, means on the motor-controller for actuating the door-latch-operating devices and connecting said motor-controller with the device 15, substantially as described.

6. In combination with an elevator-shaft, a car to move in said shaft, a door in an opening to said shaft, means for automatically opening the same, a device for latching the same in closed position, means on the car for operating said latching device, a motor-controller in said car, cams 16 arranged in said shaft, a device 15 arranged to be actuated by said cams, means on the motor-controller for actuating the door-latch-operating devices, and means for permitting the connection of the motor-controller with the device 15 only when the motor-controller has been brought to stopping position, and permitting the operation of the same after the connection has been made, substantially as described.

7. In combination, an elevator-shaft and a car to move therein, a door in an opening to said shaft, a weighted cord to open the same, a preponderating device for closing the door, means operated by the car for entirely disengaging said preponderating device from action on the door, and means in the shaft for holding the same so disengaged, a latch for holding the door closed, means for operating the same, means in the car for releasing the door-closing device and restoring the door-latch to its latching position, a motor-controller in the car, a device thereon for operating the means for releasing the door-closing and latch-restoring devices, substantially as described.

8. In combination, an elevator-shaft and a car to move therein; a door in an opening to said shaft, a weighted cord to open the same, a preponderating lever for closing the door, means operated by the car for disengaging said lever from action on the door, and means in said shaft for holding the same so disengaged, a latch for holding the door closed, means in the car for releasing the door-latch to its latching position, a motor-controlling device in the car, and a device for operating the means for releasing the door-closing and latch-restoring devices, substantially as described.

9. In combination with an elevator-shaft, and a car to move therein, a door in an opening to said shaft, means for opening the door and preponderating means for closing the door, a latch for holding the same closed, means operated by the motion of the car to relieve the door of the action of the closing

- device, a motor-controller in said car, a device on said controller operative in the stopping position only of the said controller to release the door-latch, and means compelling the restoration to action of the door-closing device and the restoration of the latch to latching position prior to the movement of the car away from said door, substantially as described.
10. In combination with an elevator-shaft, a door in an opening to said shaft, means for automatically opening the same, a latch for holding the door closed, a car in said shaft, a motor-controller in said car, means in the car for operating the latch, a device on the motor-controller for actuating the means for operating the latch, and means to prevent the operation of the said device until the motor-

controller is brought to stopping position, substantially as described.

11. In an elevator mechanism of the kind described, the combination of a motor-controlling device 11, a movable pin 11^b thereon, a plate 12 with a slot 12^a open only at the motor-stopping position of the pin 11^b, a lever 15, a spring 15^c, and lever 15^d, a link-connecting lever 15 and the spring and lever 15^d, and cams 16 to actuate the lever 15^d, substantially as described.

In testimony whereof I affix my signature in presence of two witnesses.

CASSIUS M. BARTHOLOMEW.
